UNITED STATES PATENT OFFICE.

ABRAM G. HOLMES, OF PITTSBURGH, PENNSYLVANIA.

DRAINING DEVICE FOR METER CASINGS.

Application filed October 14, 1922. Serial No. 594,520.

To all whom it may concern:

Be it known that I, ABRAM G. HOLMES, a citizen of the United States, and a resident of Pittsburgh, in the county of Allegheny and the State of Pennsylvania, have made 5 a new and useful Invention in Draining Device for Meter Casings, of which the following is a specification.

This invention relates to meters and particularly to improved means for draining 10 meter casings.

An object of the invention is to produce new and improved means for draining meter casings which simplifies the construction of 15 the casing and also the procedure of draining the casing.

A further object is to produce a new and improved means for draining meter casings which provides an effective means for sealing 20 the meter casing, and also simplifies the sealing operation.

These and other objects which will be made more apparent from the further description of the invention are attained by 25 means of apparatus embodying the features herein described and illustrated in the drawings accompanying and forming a part hereof.

In the drawings, Figure 1 is an end elevation of a meter casing embodying my invention. Fig. 2 is a side elevation of the casing shown in Figure 1, a portion being shown in section for convenience of illustration. Fig. 3 is a fragmental sectional 35 view along the line 3—3 of Fig. 2.

It is essential to provide means for removing such liquid as may accumulate within a meter casing, and this is usually accomplished by providing drainage apertures in 40 the casing which are normally closed by means of plugs. In the drawings I have illustrated a well known form of meter casing which consists essentially of a central or body portion 4 and two cover plates 5—5. 45 Each cover plate is flanged as at 7 and is secured to a flange 6 formed on the body portion 4 by means of screws. Each cover is recessed to provide a pocket 8 for receiving dirt and liquid. Such a structure necessitates drainage apertures for the portion 50 of the casing enclosed by the body portion and also drainage apertures for each pocket 8. Heretofore, it has been necessary to provide two or more drainage apertures for 55 each pocket 8, because of the construction of the cover plates.

With my invention, I not only obtain complete drainage of the plate pockets 8 with but one drainage aperture for each plate, but the structure employed by me also simplifies the operation of sealing the meter casing and making the casting. 60

Heretofore, it has been customary to provide the body portion 4 with flanges 6 such as are illustrated in Fig. 2, and which are adapted to be engaged by the flanges 7 of the cover plates. It has also been customary to secure each plate to the body 4 by means of screws spaced circumferentially with relation to flange 6. In order to insure a tight 70 fit between the end plates and the body 4 at all points around the edge of the plate, it has been necessary to provide a special form of end plate so arranged that one or more securing screws are located within the space 75 subtended by the drainage pocket. This requirement has been satisfied by providing at least one recess in the exterior face of the pocket portion of each cover plate and at least one complementary body-engaging face 80 on the inner face of each cover. The portion of the plate so formed is provided with a screw-receiving aperture and is so located and arranged that it engages an adjacent flange or lug 6^a forming a part of or co- 85 operating with the body flange 6. Such a construction however divides the lower portion of the pocket 8 of each cover plate into at least two moisture collecting cavities and means must therefore be provided for draining 90 each of these cavities. 95

With my invention I provide a cover substantially similar to the cover above described in that it is provided with a screw receiving flange 7 which extends substantially around the plate and engages the flange 6 of the body 4. This flange is interrupted by the pocket 8 of the cover, but instead of providing the usual recess for receiving a cover retaining screw 9, I provide a re-entrant flange or lug 10 on that portion of the cover subtended by the pocket 8. The flange 10 projects into the confines of the pocket 8, in effect forming a continuation of the flange 7 and engages the flange or lug 6^a of the body portion. 100

In order to drain the pocket 8 and also to provide means for securing the screw 9 in place in the registering screw receiving apertures formed in the flanges 6^a and 10, 110 I provide an aperture 11 in the wall of the pocket portion 8 which is located immedi-

ately opposite the screw receiving aperture formed in flange 10 and is preferably axially aligned with that aperture.

The spacing of the plate-holding screws is preferably such that the screw 9 is located adjacent to the lowermost part of the body 4, since under such conditions the aperture 11 may be of minimum size and yet accomplish a complete draining of the pocket 8. As shown, the aperture 11 is tapped and is adapted to receive a conical threaded plug 12 which normally closes it and which also contributes to an effective sealing for the meter casing.

The operation of assembling the casing is as follows:—The plugs 11 of each cover 5 are removed. The covers are then placed in position on the body 4 so that their flanges 7 and 10 engage the flanges 6 and 6^a and so that the screw receiving apertures in these flanges register with the tapped apertures provided in flanges 6^a and 6 of the body. Cover holding screws 9' are then employed for securing the covers in place on the body 4 and a cover locking member such as a screw 9 is introduced through the apertures 11 of each cover and is secured in place in the registering screw-receiving aperture of the flanges 6^a and 10 by means of a screw driver which is inserted through the aperture 11. The plugs 12 are then screwed into the apertures 11.

All meters are sealed for the purpose of preventing access to their interior by unauthorized individuals while the meters are in use. This is ordinarily accomplished by employing sealing wires and seals on all plugs and also by passing sealing wires through registering apertures formed in the flanges 6 and 7 of the body portion and cover plates respectively. This special precaution of sealing the cover plates in place is necessary with the ordinary meter casing because all of the cover retaining screws are accessible from the exterior of the meter.

With my invention at least one retaining screw of each cover is enclosed within the interior of the casing and therefore is not accessible when the plugs 11 are in place. The plates 5—5 will therefore be effectively sealed if the usual sealing means is employed in connection with the plugs 11. With meters embodying my invention I find that it is convenient to use a single sealing wire 13 which extends from the plugs 11 of the two cover plates through the body plugs 14 and 15. This arrangement simplifies the operation of sealing the meter since it reduces the number of sealing plugs, seal wires and lead seals 15, which must be employed to adequately prevent unauthorized tampering with the meter.

It will of course be understood that one or more apertures 11 may be employed in

each cover, depending on the necessary spacing of the cover holding screws but that it will only be necessary to employ one of these apertures as a drainage aperture, and that consequently the other apertures may be more or less permanently closed after the cover retaining screws are introduced through them.

A convenient method of introducing the screws 9 through the cover apertures 11 is to slightly peen over the edges of the slot formed in the head of the screw so that when the point of the screw driver is introduced into the screw slot the peened-over edges will grip the blade of the driver with sufficient force to hold the screw on the driver while it is being introduced through the aperture 11 and into the screw receiving aperture of the flange 10.

It will also be understood that any suitable closure may be employed for the drainage apertures and that various changes and substitutions may be made in the apparatus described and in the arrangement and location of the parts, without departing from the spirit and scope of the invention disclosed by the appended claims.

What I claim is:

1. In combination in a meter casing, a body, a cover plate recessed to form a pocket and provided with a drainage aperture for the pocket, a reentrant body-engaging member formed on the cover plate and projecting into the confines of the pocket and having a screw-receiving aperture formed therein, and located opposite to said drainage aperture, a body-engaging screw within said screw-receiving aperture, and means for closing said drainage aperture and for preventing unauthorized access to said screw.

2. In a meter casing, a body, a cover plate having a recess formed therein and provided with a drainage aperture, a re-entrant, body-engaging flange formed on the cover plate and projecting into the confines of the recess, a body-engaging member engaging said flange and located opposite to said drainage aperture, and means for closing said drainage aperture and preventing unauthorized access to said member.

3. A meter casing comprising a body, a recessed cover having a drainage aperture formed in the recessed portion thereof and a re-entrant body-engaging flange formed thereon and projecting into the confines of the recess, a member engaging said body and said flange and located opposite to said drainage aperture and within said recess, and a plug for closing said drainage aperture.

4. In combination with a meter casing comprising a body, a recessed cover having an aperture formed in the recessed portion thereof, and a re-entrant body-engaging

flange formed thereon, a cover locking member engaging said flange and said body and located within the space enclosed by the body and the cover and adjacent said aperture, a plug for closing said aperture, and means for sealing said plug in place within said aperture and preventing unauthorized access to said member.

5. In combination with a meter casing comprising a body, and a cover having an aperture formed therein, a cover securing

member adapted to be inserted through said aperture, engaging the cover and the body and located wholly within the interior of said casing, means for closing said aperture while said member is in engagement with the body and the cover, and means for sealing said closing means.

15 In testimony whereof, I have hereunto subscribed my name this eleventh day of October, 1922.

20 ABRAM G. HOLMES.
